(57) **CLAIM**

The ornamental design for a food searing tool, as shown and described.

DESCRIPTION

FIG. 1 is an exploded perspective view of my food searing tool invention;

FIG. 2 is a front elevation view of the invention, the rear view being a mirror image thereof;

FIG. 3 is a side elevation view of the invention, the opposite side view being a mirror image thereof;

FIG. 4 is a perspective view from above of an upper portion of the invention;

FIG. 5 is a perspective view from below of the upper portion of the invention;

FIG. 6 is a top plan view of the upper portion of the invention;

FIG. 7 is a bottom plan view of the upper portion of the invention;

FIG. 8 is a front elevation view of the upper portion of the invention, the rear view being a mirror image thereof;

FIG. 9 is a side elevation view of the upper portion of the invention, the opposite side view being a mirror image thereof;

FIG. 10 is a perspective view from above of a lower portion of the invention;

FIG. 11 is a perspective view from below of the lower portion of the invention;

FIG. 12 is a top plan view of the lower portion of the invention;

FIG. 13 is a bottom plan view of the lower portion of the invention;

FIG. 14 is a front elevation view of the lower portion of the invention, the rear view being a mirror image thereof; and, FIG. 15 is a side elevation view of the lower portion of the invention, the opposite side view being a mirror image thereof.

The broken lines in the drawings represent unclaimed environmental subject matter and form no part of the claim.
